THERMOELECTRIC GENERATOR WITH
PILOT BURNERHubert T. Sparrow, Minneapolis, Minn., assignor
to Minneapolis-Honeywell Regulator Company,
Minneapolis, Minn., a corporation of Delaware

Application July 31, 1942, Serial No. 453,113

20 Claims. (Cl. 136—4)

1

The present invention is concerned with a thermoelectric generator and more particularly with one adapted to be employed as a pilot burner in a burner control system.

An object of the present invention is to provide a combined pilot burner and thermoelectric generator which provides for the efficient lighting of a main burner and at the same time generates a relatively large electromotive force so that the electromotive force generated can be used for energizing a control system.

A further object of the present invention is to provide a combination of a combined pilot burner and thermoelectric generator unit and a main burner in which the main burner is adapted to heat the hot junctions of the thermoelectric generator unit to a greater extent than the cold junctions so as to increase the electromotive force generated by the thermoelectric generator unit.

A further object of the present invention is to provide a thermoelectric generator unit comprising a plurality of thermocouples so arranged as to provide for the maximum temperature differential between the hot and cold junctions and at the same time to provide a relatively compact unit.

A still further object of the present invention is to provide such a thermoelectric generator unit in which the individual thermocouples are arranged in the form of U-shaped elements with the legs of the U-shaped elements disposed on opposite sides of the burner unit.

A still further object of the present invention is to provide such a generator unit in which the cold junctions are disposed in the path of both the secondary and the primary air so that a large temperature differential is maintained between the hot and cold junctions.

A still further object of the invention is to provide such a thermoelectric generating unit in which provision is made for protecting the elements adjacent the hot junction against corrosion so as to permit the use of metal of more desirable thermoelectric characteristics than would otherwise be possible.

A further object of the present invention is to provide in connection with the burner and generating unit a new and novel burner unit which involves a minimum number of parts and which can be made in an extremely simple manner.

Other objects of the invention will be apparent from a consideration of the accompanying specification, claims and drawing, of which

Figure 1 is a front elevational view of my im-

2

proved thermoelectric generating and burner unit.

Figure 2 is a side elevational view of my generating and burner unit,

5 Figure 3 is a vertical sectional view taken along the line 3—3 of Figure 2,

Figure 4 is a transverse sectional view taken along the line 4—4 of Figure 1,

10 Figure 5 is a side elevational view of a portion of one of these thermocouple units.

Figure 6 is a view, partly schematic, of a gas burner control system employing my improved generator and pilot unit,

15 Figure 7 is a front elevational view, with portions broken away, of an alternative form of my thermoelectric generator unit,

Figure 8 is a transverse sectional view of the burner unit of Figure 7, the section being taken along the line 8—8 of Figure 7, and

20 Figure 9 is a sectional view of the burner unit of Figure 7, the section being taken along the line 9—9 of Figures 7 and 8.

Referring to Figures 1 to 4, the thermopile and burner of the present invention generally comprises a burner unit 10 (Figures 3 and 4) which is supported in a U-shaped bracket 11, around which extends a member 12 which acts as a support and cover member for a plurality of U-shaped thermocouples connected together to 30 constitute a thermopile.

Referring specifically to the burner 10, this comprises a pair of complementary members formed of sheet metal, these members being designated by the reference numerals 14 and 15 (Figure 4). Each of the members is provided with a plurality of tongues 16 (Figure 3), these tongues being bent around the edge of the adjoining member so as to retain the two members in assembled relation. Each member is stamped 40 so that its lowermost portion 19 is in the form of half a frusto-conical tube. Connecting with this grooved portion 19 and diverging upwardly is a grooved portion 20, also in the form of half of a frusto-conical tube. The upper end of the 45 grooved portion 20 joins with a further recessed portion 21 which diverges outwardly in an even greater angle terminating in a rectangular recess. The two portions 19 and 20 collectively define two frusto-conical passages joined by a narrow throat 50 so as to provide a Venturi effect. The two portions 21 collectively define a diverging passage serving to lead the gas leaving the passage 20 to the outlet of the burner. At the extreme upper end, the two members 14 and 15 are spaced apart 55 to form an elongated narrow slit 23 (best indi-

cated in Figure 4). Gas issuing through this slit, upon being ignited, results in the flame for heating the various thermocouple units. The proper spacing between members 14 and 15 is maintained by a pair of stamped projections, one extending inwardly from each of the members 14 and 15. The two projections 24 are of a predetermined depth and serve to accurately space the members 14 and 15.

In the center of each of the recessed portions 21 is a deeply grooved portion 26 which terminates at its upper end in an opening 27. The openings 27 constitute burner openings for igniting flames, which flames are of substantially greater size than the flames issuing through the slit 23, as best indicated in Figure 6. Projecting downwardly from each of the members 14 and 15 are a pair of spaced legs 29 and 30, these legs being of identical shape in the case of each member and being held closely together by reason of the clamping action of tongues 46 so as to constitute two spaced legs in effect. Similarly, adjacent the upper outer end, members 14 and 15 are each provided with a pair of ears 31 and 32. These pairs of ears likewise are identical in the case of both members so that ears 31 of the two members act as one ear while ears 32 act as a second ear. The legs 29 and 30 and the ears 31 and 32 are designed to cooperate with the U-shape supporting bracket 11. This U-shaped supporting bracket is provided with slots in its base portion into which legs 29 and 30 extend and is provided with slots in its two side legs into which ears 31 and 32 extend. The burner unit 10 is thus held rigidly with respect to the U-shaped bracket 11.

A burner reducing nipple 35 having a connecting portion 36 and a threaded tip portion 37 is secured in the base portion of U-shaped bracket 11. The tip portion 37 is threadedly secured in an opening centrally of this base portion, with the tip portion projected into the mouth of the conical passage 19. The tip portion 37 and the conical portions 19 and 20 of the burner 10 provide for the intake of primary air and the mixture of gas and air in a conventional manner.

The cover assembly 12 is formed of two cover members 39 and 40. These two members are identical and adapted to interfit with one another. Each of the cover members 39 and 40 is formed of sheet metal and is bent adjacent its edges to provide two end portions. In the case of each cover member, one end portion comprises a tongue 41, ears 43 and 44 which are turned inwardly, and ears 45 and 46 which lie in the plane of the end portion. In the case of each cover member, the other end portion comprises two ears 49 and 50 which together define a recess adapted to receive the tongue 41. This same end portion, in each case, is provided with two in-turned tongues 51 and 52, and with two further tongues 53 and 54 which extend in the plane of the end portion. It will be noted in Figure 2 that when the end portion of one member is placed against the complementary end portion of the other, the tongue 41 fits between the ears 49 and 50 and the tongues 43 and 51, on the one hand, and tongues 44 and 52, on the other hand, define two pairs of inturned tongues which are oppositely spaced from each other. Similarly, tongues 46 and 53, on the one hand, and tongues 45 and 54, on the other hand, form two pairs of aligned tongues.

Each of the ears 49 and 50 is provided with a substantially semi-circular recess which is com-

plementary to a similar semi-circular recess in the adjoining edge of tongue 41. These recesses in each case define a circular opening 55 through which a screw 56 is adapted to extend. As best indicated in Figure 3, screws 56 are threadedly engaged with the U-shaped bracket 11. The screws 56 function to maintain the cover members 39 and 40 in assembled relation with the U-shaped member 11. Furthermore, the two cover members 39 and 40 serve to increase the rigidity of the assembly comprising U-shaped bracket and burner 10 by counteracting any tendency of the legs of the U-shaped bracket 11 to spread apart and thus release the upper end of the burner.

The cover assembly 12 comprising the two cover members 39 and 40 functions not only to enclose the mechanism thus far described but also to support the series of U-shaped thermocouples which together define the thermopile of the present invention. These thermocouples and the manner in which they are supported by cover members 39 and 40 will now be described.

The thermopile comprises a plurality of elements 60 and 61 of metals of different thermoelectric characteristics. Thus the element 61 may be of "Copel" and the element 60 of "Chromel." "Copel" is an alloy comprising 55 per cent copper and 45 per cent nickel. The "Chromel" which is desirably used is an alloy consisting of 80 per cent nickel and 20 per cent chromium. The elements 60 and 61 are joined at their upper ends, as indicated by the numeral 62 in Fig. 5 to form hot junctions. Each element 60 is connected to the adjoining element 61 at its lower end, as indicated by the reference numeral 64. The junction 64 constitutes the cold junction. A sleeve 66 surrounds each pair of elements 60 and 61 adjacent their junction 62. This sleeve 66 is of stainless steel and is designed to resist heat and to protect the thermoelectric elements 60 and 61 from the corrosive action of the flame. By using such a sleeve of non-corrosive material to protect the thermoelectric elements, it is possible to employ thermocouple elements having better thermoelectric characteristics than would otherwise be possible.

The thermoelectric elements are held in position between the cover members 39 and 40 and clamping bars 70, 71, 72 and 73. The clamping bars 70, 71, 72 and 73 are formed of sheet metal stamped to provide ribs for re-enforcing purposes. The rib of clamping bar 70 is indicated by the reference character 75 and is best shown in Figure 4. In view of the fact that the ribs in connection with the other clamping bars are similar, no reference characters have been applied thereto. Cover members 39 and 40 are similarly stamped with rib portions 76, which rib portions serve to reinforce the cover members 39 and 40 and to retain ceramic spacing members 74. The clamping bars 70 to 73 are held in position by the inturned tongues 43, 44, 51 and 52. These tongues serve to firmly hold the cover members 14 and 15 and the clamping bars 70 to 73 in assembled relationship with the thermoelectric members 60 and 61 firmly secured therebetween. The ceramic spacing members 74 are provided with a plurality of grooves into which the thermoelectric members 60 and 61 fit. The members 74 thus serve to hold the members 60 and 61 properly spaced apart. Sheets 80 and 81 of insulating material are located between the thermoelectric elements and the cover members. I have conveniently employed sheets of mica for this purpose. Strips 83, 77, 78,

and 78 of similar insulating material are disposed between clamping bars 70, 71, 72 and 73, respectively, and the thermoelectric elements 60 and 61. It will be noted that the thermoelectric elements are surrounded on both sides by insulating material and are thoroughly insulated from each other.

As best shown in Figure 6, the central portion of sleeve 66 surrounding the hot junction 62 is heated by a central runner flame 89 issuing from the opening 23 of burner 10 and extending the full width of the burner. Issuing from opening 27 are igniting flames 90 and 91, which flames are employed to ignite the main burners 100 and 101, respectively.

It will be noted that the thermoelectric elements 60 and 61 form a series of U-shaped thermocouples, the legs of which straddle the burner. This results in a very compact structure and utilizes to the utmost the cooling effect of the incoming gas and air as will be pointed out more fully later. Furthermore, the bends of the thermocouples form a cage enclosing the runner flame 89 and protecting it against extinguishment.

The manner in which the improved thermoelectric generator unit is employed in a burner system is illustrated schematically in Figure 6. As shown in this figure, the generating unit is employed to energize the electromagnetic pilot valve of a diaphragm valve. This diaphragm valve 95 may be of any conventional type in which a sensitive electromagnetic pilot valve controls the pressure applied to a diaphragm positioning the main valve. Such valves are well known and it is believed unnecessary to illustrate specifically such a valve. The type of valve which I have found particularly desirable to employ in connection with such a generator and in such a system as shown in Figure 6 is the valve shown in my copending application Serial No. 437,541, filed April 3, 1942, and issued as Patent No. 2,393,427 on January 22, 1946.

The valve assembly 95 is provided with two electrical terminals 96 and 97 which are connected to the ends of the winding of the electromagnetic pilot valve. The valve assembly is further provided with a bleed opening 94 which is connected with a pipe 93 leading to a bleed burner 98. When a source of power is connected across terminals 96 and 97 the electromagnetic valve is moved to such a position that the gas from the pressure chamber formed by the diaphragm is bled off to the bleed burner 98 and the diaphragm moves the main valve to open position. When power is removed from terminals 96 and 97, the pilot valve moves to a different position in which the escape of gas from the controlling chamber through pipe 93 and bleed burner 98 is prevented with the result that pressure builds up within the diaphragm chamber and causes the main valve to move to closed position.

The valve assembly 95 controls the flow of gas to a plurality of main burners 100 and 101, being connected thereto by pipe 103. The pilot burner and generator unit is rigidly mounted with respect to burners 100 and 101 so that the flames 90 and 91 issuing from openings 27 just extend over the inner ends of the burner in a position to ignite gas issuing from the end burner jets. The hot junctions of the thermopile are located at a position closely adjacent to the main burner jets so as to be affected appreciably by the heat of the main burner. The cold junctions, on the other hand, are located a substantial distance below the main burner. This is possible because of the relatively great length of the thermocouple. Due to this difference in position of the hot and cold junc-

tions, the cold junctions are located in a relatively cool portion of the burner. As is well known, the temperature within a burner chamber drops sharply below the main burner due to the inrush of primary air. By providing relatively long thermocouples, it is possible to have the cold junctions only slightly affected by the main burner while the hot junctions are appreciably affected thereby. The result is that the thermopile is additionally heated by the main burner to supplement the action of the pilot burner flame.

The thermopile not only acts as a safety device to insure closure of valve assembly 95 when the thermopile is not heated as a result of the pilot burner being extinguished but is also operative to supply current for the operation of the valve. Current is supplied to the valve assembly 95 under the control of a thermostat 107. This thermostat is of conventional form comprising a bimetallic element 108 to which is connected a contact arm 109 movable into and out of engagement with a fixed contact 110. As indicated by the legend adjacent the thermostat, the bimetallic element 108 is effective to move contact arm 109 towards the right into engagement with contact 110 when the temperature drops. While the thermostat is illustratively assumed to be responsive to the temperature of a space, it is to be understood that the thermostat can be responsive to any other desired controlling temperature condition. As far as the present invention is concerned, the thermostat 107 may be replaced by any controlling switch.

The pilot burner assembly is supplied with gas through a pipe 115 connected to the inlet chamber of valve 95. Normally, the pilot burner is constantly burning. Figure 4 clearly shows the side walls of the burner 10 spaced from the cover 12 and also the top and bottom of the cover to be open. This construction provides a passage for the flow of air through the device. The gas passing through nipple 37 and the Venturi throat formed by passages 19 and 20 draws with it primary air which is mixed with the gas in a conventional manner. It is to be noted that because the lower ends of the thermocouple elements extend below the casing 12, this air passes over the cold junctions serving to cause cooling thereof. The mixture of gas and air issues from openings 27 and from slit 23 to form flames 89, 90, and 91. This discharge sets up an aspirating action which draws secondary air through the space between the burner and the cover and thus over the exposed thermocouple elements 60 and 61. Therefore not only are the cold junctions 64 cooled by the primary air entering the Venturi throat 19 but they are also cooled by the secondary air which is drawn up through the burner casing to support combustion. Also, the incoming gas contributes to the cooling effect. Thus, under normal circumstances, the thermoelectric unit generates a substantial electromotive force. The amount of this electromotive force is materially increased by reason of the fact that the air and gas which serve to support combustion and increase the temperature of the hot junctions also serve to cool the cold junctions and hence increase the temperature differential between the hot and cold junctions.

Whenever the thermostat 107 calls for heat, that is, when the temperature to which the bimetallic element 108 drops sufficiently to cause closure of switch blade 109 against contact 110, an energizing circuit is established between terminals 96 and 97 as follows: from the thermoelectric

generating unit through conductor 117, bimetallic element 108, switch blade 109, contact 110, conductor 118, terminal 96, the electromagnetic unit of the pilot valve, terminal 97, and conductor 119 back to the generator unit. If the pilot burner is properly ignited, the generator unit serves to supply power to the electromagnetic unit to cause the pilot valve to move to such a position that the gas in the pressure chamber bleeds off through pipe 93 and burner 98 permitting the diaphragm to move the main valve to open position. Gas issuing from bleed burner 98 is ignited by the igniting flames 90 and 91. Similarly, the gas supplied through pipe 103 to main burners 100 and 101 as a result of the opening of the main valve is likewise ignited by the igniting flames 90 and 91. The operation of main burners 100 and 101 tends to increase the temperature differential between the hot junctions 62 and the cold junctions 64, as previously explained. This increase in differential by reason of the operation of the main burner is not sufficient, however, to prevent the pilot valve from moving to valve closing position if the pilot burner is extinguished. It is desirable in normal applications that the main burner be extinguished if the pilot burner is at any time extinguished. Hence, if the pilot burner should be extinguished the electromotive force generated by the thermopile unit will drop to a lower value than that caused by the temperature differential produced by both the pilot burner and the main burner. This lower value is such that the electromagnetic pilot valve will not remain in the position in which the main valve is open but will move to its other position, interrupting the escape of gas through bleed pipe 93 and causing pressure to be applied to the main diaphragm chamber to cause closure of the main valve, and hence to interrupt the flow of gas to the main burners 100 and 101.

Under normal circumstances, however, the pilot burner remains ignited so the gas continues to flow to main burners 100 and 101 until such time as the thermostat 107 is satisfied. When this happens, switch blade 109 is moved out of engagement with contact 110 so as to interrupt the circuit previously traced. This, in turn, results in the deenergization of the electromagnetic pilot valve to cause it to move to a position in which the main valve is moved to closed position.

It will be seen that I have provided a thermopile unit which can be produced inexpensively from simple stamping operations. The elements of the thermopile, furthermore, are so arranged as to result in the generation of the maximum possible thermoelectric force.

Species of Figures 7, 8 and 9

In Figures 7, 8 and 9, I have provided a somewhat modified form of pilot burner and generator unit. In this modification, the burner and the means for supporting the thermocouples are combined in a single cast member 125. This casting comprises a base portion 127 of substantially square cross-section having a tubular stem portion 128 projecting upwardly therefrom and communicating with a horizontal tubular portion 129 provided with a plurality of burner openings 130. The stem portion 128 and horizontal portion 129 form a T-shaped burner unit. Secured to the rectangular base portion 127 are a pair of spaced walls 133 and 134.

Referring first to the base portion 127 of square cross-section, this is provided with a cylindrical recess 136 which is threaded at its lower end to

receive a threaded bushing 137. Threadedly secured within this bushing 137 is a jet member 138 which is provided at its upper end with a tip 139 and at its lower end with a threaded nipple 140 designed to be connected to a conduit for supplying gas to the burner. Two opposed openings 142 (only one of which is shown) extend through the walls of the cylindrical recess 136 and serve for the introduction of primary air.

10 The upper end of the cylindrical recess 136 connects through a conical passage 144 with a passage 145 in the stem portion 128. These passages serve as a mixing chamber for gas and air. The stem portion 128, as best noted from a comparison of the dotted line shown in Figure 7 and the full-line showing in Figure 8, is of square cross-section. This passage 145 in turn communicates with a horizontal passage 146 extending through the horizontal tubular portion 129. The 15 passage 146 in turn serves to supply gas to the plurality of burner openings 130 spaced at uniform intervals along the tubular member 129.

The walls 133 and 134 are integrally secured to the base portion 127 and are integrally connected to the horizontal tubular portion 129 by connecting ribs 150 and 151. The walls 133 and 134 are channeled to accommodate the various thermocouple members, as will be presently explained. As best seen in Figure 9, the walls are 20 spaced from the burner to allow a free flow of secondary air.

25 Located on top of the casting 125 is a cage member 156 of ceramic material. This cage member is provided with end walls 157 having openings 158 therethrough and side walls 160 and 161. The cage member 156 serves to support the hot junctions of the thermocouples in proper spaced relation with respect to the burner jet 30.

30 A plurality of thermocouple elements 170 and 171 are mounted on member 125 and cage member 156. These elements are of materials of suitably dissimilar thermoelectric characteristics such as "Copei" and "Chromel," the two alloys mentioned in a previous portion of the specification. 35 In the case of every thermocouple, the elements 170 and 171 are connected together to form a hot junction 172. As with the previously described species, a tube 173 of flame resistant material such as stainless steel is located around the elements 170 and 171 adjacent the hot junction 172. This stainless steel tube 173 serves to protect the thermoelectric element 171 from the 40 corrosive action of the flame.

The lower ends of the thermocouple elements 45 170 and 171 are reduced in diameter to form relatively thin terminal portions 175 and 176. These thin terminal portions are connected together at their lower ends, as indicated by the reference numeral 177. The junctions 177 constitute the cold junctions of the thermopile. By 50 reducing the material adjacent the cold junctions, it is possible for the cold junctions to be maintained at a lower temperature by the primary and secondary air and to cool off relatively quickly 55 when the flame is extinguished.

The thermopile consisting of elements 170 and 171 is located over the casting 125 and the cage 156 of ceramic material with the horizontal uppermost portions of the elements 170 and 171 resting on the upper edges of side walls 160 and 161 of cage element 156. The leg portions of the thermocouple elements 170 and 171 extend downwardly on opposite sides of the casting 125 and are held in position by a pair of plates 186 and 187 which are slidably mounted in grooves in

the walls 133 and 134. Sheets 178 of insulating material are disposed on opposite sides of the legs of the thermocouple elements 170 and 171 and serve to insulate these elements from the main casting 125 and from the plates 186 and 187. The casting 125 and the plates 186 and 187 together with the cage member 156 serve to securely hold the thermocouple members in assembled relationship.

In order thoroughly to insure that the flame issuing from jets 130 will not contact the thermocouple elements, a coating of ceramic material 180 is applied to the thermocouple elements on each side of the sleeve 173, this coating joining with the side walls 160 and 161 of the cage 156 of ceramic material and serving to completely enclose the portions of the thermocouple elements 170 and 171 entering the stainless steel tubes 173.

It is believed that the operation of the burner unit of Figures 7, 8, and 9 will be obvious from the preceding description. The gas entering through the jet 138 draws with it air through the primary air openings 142. A mixture of the gas and air passes up through passages 145 and 146 and out through the burner openings 130 resulting in a series of flames for the full width of the burner unit. These flames are protected from extinguishment by the cage 156. The flames extend through the stainless steel tubes 173, heating these tubes and thus heating the hot junction 172. Unlike the arrangement of Figures 1 to 6, the same flames act to heat the hot junction and to ignite the main burner. As with the previous species, but to a slightly lesser extent, the incoming primary and secondary air cools the cold junctions 171. Because of the thermocouples being reduced adjacent the cold junctions, the thermal mass of the cold junctions is less and it is easier for the air to maintain them at a low temperature.

Due to the combined action of the ceramic cage 156 and the ceramic coating 180, the elements 170 and 171 are thoroughly protected from the corrosive action of the flame.

In both of the modifications, the combined burner and thermoelectric generating unit is relatively compact and by reason of the relatively great resistance to transfer of heat between the hot and cold junctions, is capable of generating an electromotive force of substantial magnitude.

In general, while I have shown certain specific embodiments of my invention, it is to be understood that this is for purposes of illustration and that my invention is to be limited only by the scope of the appended claims.

I claim as my invention:

1. A combination electric generator and pilot burner device comprising, a plurality of thermocouples electrically connected in series, a pilot burner member having an elongated and relatively narrow slot at one end thereof for producing a thermocouple heating flame and having larger orifice means therein as igniter producing means, said burner having an opening at the opposite end thereof for the admission of gas and primary air thereto, sleeve members for protecting the hot junction of the thermocouples, insulated casing means for insulating and supporting the thermocouples with one leg of each thermocouple on opposite sides of the said burner and with the hot junctions spaced from the pilot burner in a row extending parallel with said narrow pilot burner slot to be thus subjected to substantially the highest temperature produced by

proper operation of the pilot flame, and the said sleeve members supporting the cold junction end portions of the thermocouples in a position below the said burner and sleeve members and in the path of the flow of primary air into the said pilot burner.

2. A combination comprising, a plurality of U-shaped wire thermocouple members connected in series to form a thermopile, a metallic flame-protecting sleeve for the hot junction of each of said thermocouple members, the said hot junction covering sleeve of the said thermocouple members being bent to retain the sleeve members in their proper position and to form the curved portion of the U-shaped thermocouple members, insulated casing means for mounting the leg portions of the U-shaped series connected thermocouple members parallel with each other and with the hot and cold junction ends thereof extending beyond the said casing, gas burner means having a mixing chamber for mixing gas with primary air, means for insulating the burner from the thermocouple members and for mounting the burner means within the said thermocouple casing means, supporting means including a bracket member for supporting the said casing together with the gas supply line for the burner and the connecting leads for the thermopile, the said supporting means surrounding the cold junctions of the thermocouple members extending beyond the said casing and said mixing chamber of the burner, said casing, said bracket and said gas burner being disposed to induce a flow of secondary air to bathe said cold junctions and then flow along exposed portions of said thermocouples intermediate said burner and said casing and to induct a flow of primary air to bathe said cold junctions and then pass into the mixing chamber of said burner, and the said hot junctions and protecting sleeves extending beyond the casing and burner to a position in which they are subjected to substantially the highest temperature produced by the burner flame.

3. The combination comprising, a thermopile formed of a series of thermocouple units, each of said thermocouples comprising a U-shaped unit with the two leg portions of dissimilar thermoelectric properties and having the leg portions joined to form a hot junction, a sleeve member for protecting the said hot junction, the said leg portions and sleeve member being shaped to form the angular portion of said U-shaped unit, means including a cover member for insulating and supporting the leg portions of the thermocouple units in a row and for maintaining the respective legs and hot junctions in alignment with each other, the end portions of each of the legs of said units being joined to the adjacent unit to thus connect the cold junctions of the units in series for completing the thermopile, a burner member located in the said casing and having a nozzle spaced from the said hot junctions for the uniform heating of each of said hot junctions, the said burner forming a Venturi orifice at one end thereof, and a fuel supply line cooperating with said Venturi orifice and the orifice serving to provide for the flow of fuel and primary air to the said burner, means for securing said burner and cover members together in spaced relation so as to provide for a circulation of burner secondary air between the burner and cover, and the said cold junctions being extended from the said cover and burner to a position in the path of the flow of the primary and secondary burner air for maintaining a sub-

11

stantial difference in temperature between the hot and cold junctions upon operation of the burner.

4. In combination, a burner comprising a pair of members of sheet material, means carried by each member for securing said members together adjacent their edge, said members being flared inwardly and then outwardly at their lower ends, said members being superposed on each other whereby they collectively define a Venturi throat, said members being so formed at their upper ends as to provide a narrow slit extending substantially the full width of said burner, means near the upper ends of said members to retain the central portions of the upper ends in proper spaced relation, and a casing telescoped over said members in closely spaced relation thereto whereby a secondary air passage is formed.

5. In combination, a burner comprising a pair of members of sheet material, each of said members having tongues bent around the edge of the other member to retain them together, said members being flared inwardly and then outwardly at their lower ends, said members being superposed on each other whereby they collectively define a Venturi throat, and said members being so formed at their upper ends to form a narrow slit extending substantially the full width of said burner, means for maintaining said slit uniform throughout its entire length, a bracket to which said burner is attached, and a sleeve of sheet material secured to said bracket and encasing said members, the side walls of said sleeve and said members being spaced apart.

6. In combination, a burner block having a central burner portion and a pair of walls on opposite sides of the burner portion and spaced therefrom, a hollow member of ceramic material disposed on said walls, and a U-shaped thermocouple straddling said burner block and said ceramic member, the hot junction of said thermocouple being located in the bend of the U-shaped thermocouple and the cold junction being near said means, and said bend resting on said hollow member with the hot junction in the path of the flame from said burner portion.

7. In combination, a burner block having a central T-shaped burner portion and a pair of walls on opposite sides of the burner portion and spaced therefrom, a hollow member of ceramic material disposed on said walls, and a plurality of connected U-shaped thermocouples straddling said burner block and said ceramic member, the hot junctions of said thermocouples being located in the bends thereof, and said bends resting on said hollow member with the hot junctions in the path of the flames from said burner portion.

8. In combination, a burner block having a central burner portion and a pair of walls on opposite sides of the burner portion and spaced therefrom, a hollow member of ceramic material disposed on said walls, a plurality of connected U-shaped thermocouples straddling said burner block and said ceramic member, the hot junctions of said thermocouples being located in the bends thereof, and said bends resting on said hollow member with the hot junctions in the path of the flames from said burner portion, sleeves of non-corrosive material surrounding said hot junctions, and a covering of ceramic material molded around the ends of said sleeves.

9. In combination, a burner comprising a pair of members of sheet material each having a discharge aperture therein, means for securing said

12

members together adjacent their edge with the central portions thereof spaced from each other, said members being flared inwardly and then outwardly at their lower ends, said members being superposed on each other whereby they collectively define a Venturi throat, each of said members having a deep vertical groove communicating at one end with said throat and at the other end with said discharge aperture, the concave portions of said grooves facing each other so that said grooves collectively define a passage therebetween, the upper portions of said members being flared outwardly as to width and inwardly toward each other, and each of said members having an inwardly extending projection in said upper portion adapted to engage the other member to retain the central portions of the upper edges of said members in such spaced relation as to define a relatively long narrow slit extending substantially the full width of the upper portions of said members.

10. In combination, a combination pilot burner and thermopile unit, said pilot burner being of the type burning a mixture of gas and primary air and having outlet means providing a runner flame for heating the hot junctions of said thermopile and for igniting a burner, said thermopile having leg portions sufficiently long to provide a substantial difference in temperature between the hot and cold junctions upon proper operation of the thermopile heating runner flame of the pilot burner, a cover comprising an open ended sheath encasing said pilot burner, the sidewalls of said sheath being spaced from the sidewalls of said pilot burner and providing means for directing a flow of secondary air therebetween when said pilot burner is in operation, means for supporting the thermopile in a position adjacent to and extending beyond the body portions of said pilot burner, said supporting means maintaining the legs associated with each hot junction in a position astride opposite sides of the pilot burner and also maintaining the hot junctions in a position spaced above the pilot burner to be responsive to substantially the highest temperature resulting from the proper operation of the thermopile heating flame of the pilot burner, the said extended leg portions having the cold junctions spaced from the burner, and means for directing a flow of primary and secondary burner air over said cold junctions to maintain a substantial difference in temperature between the cold and hot junctions of the thermopile upon proper operation of the thermopile heating flame of the pilot burner.

11. In combination, a pilot burner and thermopile unit comprising a relatively flat pilot burner unit with outlet means for producing a horizontal runner flame and a plurality of vertically extending thermocouple units spaced from said pilot burner with the hot junctions disposed in a horizontal straight line above said outlet means, said thermocouple units being relatively long as compared with the body portion of said pilot burner, an open ended cover telescoped over said thermocouple units and providing a shield for a portion thereof, said cover being spaced from the pilot burner to provide an air passage therebetween, a portion of said thermocouple units being disposed in said passage, and means for maintaining said cover and said pilot burner in their relative positions with the cold junctions of the thermocouple units in the space between the pilot burner and cover and subjected to a

current of air flowing therethrough to said pilot burner.

12. In combination, a pilot burner and thermopile unit comprising a relatively flat burner with air and fuel inlet at one end and outlet means for producing a runner flame at the other end thereof, a plurality of vertically extending thermocouple units spaced from said pilot burner and having the hot junctions thereof disposed in a horizontal straight line above said flame opening, a shield telescoped over the intermediate portion of said thermocouples and providing a conduit for the passage of air between said burner and said shield, means for maintaining said shield and said burner in their spaced positions, and the cold junctions and intermediate portions of said thermocouples being disposed within said conduit to be affected by the passage of air therethrough.

13. In combination, a pilot burner and a thermopile unit comprising, a relatively thin burner with outlet means for producing a horizontal runner flame and a plurality of U-shaped thermocouples, said pilot burner and said U-shaped thermocouples being disposed in spaced relation with the hot junctions in alignment above said flame opening and the cold junctions and intermediate portions of each of said thermocouples on opposed sides of said relatively thin burner, a cover positioned over the intermediate portions of said thermocouples, means for maintaining said thermocouple units in association with said cover, said last named means being spaced from said pilot burner and providing a passage for the flow of air therebetween, and supporting means for maintaining said cover and said pilot burner in their relative positions.

14. The combination comprising, a thermopile formed of a series of thermocouple units, each of said thermocouple units comprising a U-shaped member with the two leg portions thereof of dissimilar thermoelectric properties and having end portions thereof joined to form a hot junction, and a sleeve member for protecting the said hot junction, the said joined portion and sleeve being shaped to form the bend of said U-shaped unit, means including a cover member for insulating and supporting the units in spaced relation with the hot junctions in a single aligned row and the leg portions in two aligned rows, the ends of the legs of said units being joined to the end leg portions of adjacent units to thus electrically connect the cold junctions for forming a thermopile, said burner being operably positioned within said assembled U-shaped thermocouple units, and means for maintaining said burner spaced from said insulating and supporting means.

15. The combination comprising, a U-shaped thermocouple unit, the two leg portions of said U-shaped unit having dissimilar thermoelectric properties and being joined to form a hot junction, a sleeve like member for protecting the said hot junction, the said leg portions adjacent the said hot junction of said unit and said sleeve member being shaped to form the bend of said U-shaped unit, a fuel supply line, a burner having a burner nozzle at one end thereof and a Venturi orifice at the other end thereof, said fuel line being disposed to direct fuel into said Venturi orifice and thereby induce a flow of primary air through said orifice and into said burner, and means for insulating and supporting the burner between the leg portions of said thermocouple unit with the hot junction spaced from the burner to receive the maximum heat from the flame produced by the

burner, the said supporting means maintaining the cold junctions of the unit spaced from the said burner and extending to a position in which they are subjected to the flow of primary air into said burner.

16. In combination a fuel burner having at one end thereof orifice means to produce an elongated flame and at the other end an inlet for the admission of fuel and air thereinto, and a thermopile comprising a plurality of hot junctions connected in alternate series with a plurality of cold junctions, said thermopile being positioned with said hot junctions spaced in a single row above said burner and in heat conducting relation with the burner flame and the said cold junctions being located in spaced parallel rows on opposite sides of said burner and adjacent said inlet, said hot junctions being positioned to span said elongated flame, supporting means for maintaining said thermopile and said burner in said spaced association, a cover member encasing a portion of said associated burner and thermopile and forming a secondary air passage therebetween and cooperating with said supporting means to provide an air passageway to said inlet and to said secondary air passage, and said cold junctions being positioned in said passageway.

17. In combination a fuel burner having an inlet and an orifice for the escape of fuel therefrom, and a thermopile comprising a plurality of hot junctions connected in alternate series with a plurality of cold junctions, said thermopile being positioned with said hot junctions aligned above and spaced from said orifice and in heat conducting relation with the flame of said burner and said cold junctions being divided, aligned and spaced from opposite lower sides of said burner, means for maintaining said hot and cold junctions in their respective alignments and spaced from said burner, said maintaining means being spaced from said burner and cooperating therewith to provide passage means for the induction of combustion air to the inlet of said burner and to the space between said maintaining means and said burner, and the cold junctions and intermediate portions of said thermopile being positioned so as to be cooled by the flow of combustion air into and through said passage means.

18. In a combination pilot burner and thermopile unit, a burner having a passage therein, said passage having an air inlet, a fuel supply means spaced from and arranged to discharge fuel into said passage, a wall surrounding said burner and spaced therefrom, said wall in conjunction with said burner providing a second passage having an air inlet for the flow of air induced therethrough when the device is in operation, the air inlets of the first mentioned passage and said second passage being adjacent each other, a thermopile unit having hot junction portions of inverted U-shape and positioned to provide a protective cage over the flame issuing from the discharge portion of said burner and to be heated thereby, and cold junctions disposed in front of the air inlets to said passages.

19. In combination, a pilot burner having an air and fuel inlet at one end and an orifice at the other end thereof, a plurality of thermocouples each having two legs of thermoelectrically dissimilar material joined at one end to each other to form a hot junction and joined at their lower ends to other of said thermocouples to form cold junctions, and means for mounting said thermocouples in spaced relationship with respect

to said burner with said hot junctions above said orifice and with said legs extending downwardly on opposite sides of said burner, said means comprising a casing surrounding the burner and the intermediate portions of said thermocouples and with the lower end thereof terminating close to but spaced from said cold junctions and said air and fuel inlet to provide a secondary air inlet and passage between said pilot burner and said means for mounting said thermocouples.

20. An electric generator comprising a burner having an orifice at one end thereof and a primary air opening at the other end thereof, a thermocouple mounted thereon with its hot junction substantially in alignment with said orifice and its legs extending substantially parallel to and in spaced relationship with the side of the burner and with its cold junction in front of said air opening, a wall extending generally parallel with said burner with a portion of a leg of said thermocouple therebetween, said wall thus providing a secondary air passage between said wall and the side of the burner with one end of said wall terminating close to but spaced from said primary air opening and said cold junction so that air flowing into said primary air opening and said secondary air passage will pass over or adjacent to said cold junction.

HUBERT T. SPARROW.
